Specification for Design.

Patented Feb. 10, 1920.

Application filed August 9, 1919. Serial No. 316,497. Term of patent 7 years.

To all whom it may concern:

Be it known that I, GEORGE V. STRAHAN, a citizen of the United States of America, and a resident of the city of Newark, in the county of Essex and State of New Jersey, have invented a new, original, and ornamental Design for a Ceiling-Plate for Lighting-Fixtures, of which the following description, in connection with the accompanying drawings, is a specification.

The single figure of the drawing is a perspective view of a ceiling plate for a lighting fixture, showing the new design.

I claim as my invention:

The ornamental design for a ceiling plate for a lighting fixture, as shown.

GEORGE V. STRAHAN.
